Des. 211,875

Patented Aug. 6, 1968

211,875

VENT COVER FOR STANDPIPES OR THE LIKE

William V. Porter, 173 Seale Road,
San Antonio, Tex. 78219

Filed July 11, 1967, Ser. No. 7,758

Term of patent 14 years

(Cl. D23—41)

Fig. 1

Fig. 2

Fig. 3

Fig. 4

Fig. 5

Fig. 6

FIGURE 1 is a perspective view of a vent cover for standpipes or the like showing my new design;

FIGURE 2 is a longitudinal vertical sectional view thereof;

FIGURE 3 is a bottom plan view thereof;

FIGURE 4 is a perspective of a vent cover for standpipes or the like showing my new design;

FIGURE 5 is a bottom plan view thereof; and

FIGURE 6 is an end elevational view thereof.

I claim:

The ornamental design for a vent cover for standpipes or the like, as shown and described.
